(57) **ABSTRACT**

A lifting apparatus having a bar with a shoulder bar supportable on a lifter's shoulders and a weight sleeve configured to receive at least one weight. The lifting apparatus includes an adapter that allows adjustment of the distal member to one of a plurality of different positions relative to a longitudinal axis of the shoulder bar.

FIG. 3

MULTI-POSITION STRENGTH BAR

CROSS REFERENCE TO RELATED APPLICATIONS

This application is a continuation of U.S. patent application Ser. No. 17/837,012 filed Jun. 9, 2022, which is a divisional of U.S. patent application Ser. No. 16/381,885 filed Apr. 11, 2022, which claims benefit of priority to U.S. Provisional Application Ser. No. 62/656,830 filed on Apr. 12, 2018.

BACKGROUND

The subject matter of this application relates to exercise equipment and more particularly to a weight-lifting apparatus.

Athletes, fitness enthusiasts, and others continuously seek new techniques to increase strength and performance. Many such persons engage in weight training to increase strength or otherwise improve muscular function, which may include the use of either free weights and/or weight machines. One problem experienced by those engaged in weight training is that a person can potentially strain their spine, leading to pain and discomfort. Although some degree of weight-bearing is essential for spinal health, too much weight on the spine during weight training can cause spinal discs to move or bulge, and furthermore, exercises that increase the axial load on the spine are especially prone to increase spine strain and back pain.

One type of lifting exercise prone to spinal strain or injury is a "squat" in which a lifter balances a weighted bar on the shoulders (either in back of or in front of the neck), bends the knees to a squatting position, and lifts the weighted bar back to a standing position. This particular exercise requires careful technique to avoid injuries since the forward-position of the weighted bar relative to the lifter's center of gravity as the person squats, creates stress, particularly on the shoulders and back.

What is desired, therefore, is an improved exercise apparatus for performing squats.

BRIEF DESCRIPTION OF THE DRAWINGS

For a better understanding of the invention, and to show how the same may be carried into effect, reference will now be made, by way of example, to the accompanying drawings, in which:

FIG. 1 shows an exemplary improved exercise bar having an adapter that interconnects a shoulder bar with a weight sleeve;

FIG. 2 shows a close-up view of the adapter of FIG. 1;

FIG. 3 shows a plurality of positions allowed by the adapter of FIG. 2.

DETAILED DESCRIPTION

Referring to FIG. 1, an improved strength-training apparatus **10** may include an elongate shoulder bar **12** with a central support pad **14** from which two handles **16** project. In use, a lifter preferably places the support pad over the shoulders behind the lifter's neck, with the lifter's hands grasping the handles **16** firmly. In a preferred embodiment, the handles **16** may include a knurled or roughened surface **17** to prevent the lifter's grip from slipping when using the bar **12**. Those of ordinary skill in the art will recognize that

some embodiments of the bar **12** may not include the support pad **14** and/or the handles **16**.

The strength training apparatus **10** includes, at each end, a respective weight sleeve **18** upon which a desired amount of weight may be loaded upon the strength-training apparatus **10**. The weight sleeve **18** is preferably configured to be inserted into one or more Olympic-sized weights, which typically have central apertures of approximately two inches in diameter.

Referring also to FIG. 2, the weight sleeve **18** is laterally offset from the shoulder bar **12** by an adapter **20** having an angular adjustment interface **24** allowing rotation of the weight sleeve **18** about the longitudinal centerline of an inserted shoulder bar **12**, and a radial adjustment interface **22** which allows the weight sleeve **18** to be adjusted in a radial direction relative to the axis of rotation of the angular adjustment interface **24**. The combination of the radial adjustment interface **22** and the angular adjustment interface **24** allows a lifter to position the weights on the weight sleeve **18** in any one of a plurality of locations relative to the lifter's shoulders. In this manner, lifters can adjust the weights to a position that relieves stress while performing squats, or to simulate different types of squats (front, back, safety, etc.) with a single bar supported on the lifter's shoulders behind the neck.

In some embodiments, adjustment of either or both of the radial adjustment interface **22** and the angular adjustment interface **24** may allow continuous adjustment to any position desired throughout a range of adjustment. In other embodiments, the radial adjustment interface **22** and/or the angular adjustment interface **24** may allow incremental adjustment to one of a plurality of fixed positions within a range of adjustment. For example, as shown in FIG. 2 the radial adjuster **22** may be an elongate member **26** that defines a plurality of recesses **28** extending in an axial direction away from the axis of rotation of the angular adjustment interface **24**, each of the plurality of recesses **28** capable of releasably and securely retaining a distal end of a weight sleeve **18**. Preferably, each of the recesses **28** of the radial adjustment interface is sized to securely retain a weight sleeve configured to be inserted into an Olympic-sized weight. In some embodiments, such as the one shown in FIG. 2, the plurality of the recesses **28** form a contiguous slot. In such embodiments, the radial adjustment interface **22** may be configured to hold the weight sleeve **18** at a selective one of a plurality of axial positions approximately 1.5 inches from each other. Though FIG. 2 shows a radial adjuster with four such positions, other embodiments may include more or less such incremental positions.

Similarly, the angular adjustment interface **24** may in some embodiments have a plurality of fixed angular positions about which the adapter **20** may rotate. In a preferred embodiment, for example, the angular adjustment interface **24** includes an aperture formed by a periphery defining a plurality of notches, each notch configured to engage an edge of a polygonal-shaped distal end **30** of the shoulder bar **12**, which in FIGS. 1 and 2 is shown as a hexagonal protrusion. Preferably, in this embodiment, the aperture includes sufficient notches to allow adjustment of the hexagonal end of the shoulder bar to at least six locations. As shown in FIG. 2, there are twelve notches, allowing adjustment to twelve independent angular orientations, though one of ordinary skill in the art will recognize that any desired number of orientations may be achieved. Preferably, the angular adjustment interface **24** includes an end cap having a threaded connection that may be matingly received in a

bore within the weight bar 12 to secure the angular adjustment interface 24 in the desired position.

As can be seen in FIG. 3, the combination of the radial adjustment interface 22 and the angular adjustment interface 24 allows a lifter to use the adapter 20 to position weights in any of a multitude of positions around the lifters body, extending 360-degrees around the weight bar 12 and many at different radial distances from the weight bar 12, thereby allowing a lifter position weights at an optimal location for spinal safety, while achieving a number of different types of squats, e.g. a front squat, a back squat, a safety squat etc. Those of ordinary skill in the art will appreciate however, that different adapters 20 may limit the angular or radial orientation of the adapter 20 relative to the weight bar 12 to a desired range less than 360 degrees.

It will be appreciated that the invention is not restricted to the particular embodiment that has been described, and that variations may be made therein without departing from the scope of the invention as defined in the appended claims, as interpreted in accordance with principles of prevailing law, including the doctrine of equivalents or any other principle that enlarges the enforceable scope of a claim beyond its literal scope. Unless the context indicates otherwise, a reference in a claim to the number of instances of an element, be it a reference to one instance or more than one instance, requires at least the stated number of instances of the element but is not intended to exclude from the scope of the claim a structure or method having more instances of that element than stated. The word "comprise" or a derivative

thereof, when used in a claim, is used in a nonexclusive sense that is not intended to exclude the presence of other elements or steps in a claimed structure or method.

The invention claimed is:

1. An adapter for a weight lifting apparatus, the adapter configured to removably retain a shoulder bar supportable on a person's shoulders and removably retain a weight sleeve, the adapter

configured to selectively lock a retained weight sleeve into a desired one of a plurality of predetermined angular positions about an axis of rotation extending longitudinally through the shoulder bar, to prevent rotation of the retained weight sleeve about the axis of rotation; and

the adapter defining a plurality of locked radial positions of the retained weight sleeve, each radial position extending in a radial direction away from the axis of rotation by a distance different than that of the other of the plurality of locked radial positions.

2. The adapter of claim 1 wherein the retained weight sleeve is configured to be inserted into an Olympic-sized weight.

3. The adapter of claim 1 wherein the plurality of predetermined angular positions includes at least six angular positions.

4. The adapter of claim 1 in combination with the shoulder bar and the retained weight sleeve.
